UNITED STATES PATENT OFFICE

CHARLES GAY, OF NEW HAVEN, CONNECTICUT.

VIATICUM CABINET-ALTAR.

1,036,604.

Specification of Letters Patent. Patented Aug. 27, 1912.

Application filed December 28, 1910. Serial No. 599,670.

To all whom it may concern:

Be it known that I, CHARLES GAY, a citizen of the United States, and a resident of New Haven, in the county of New Haven 5 and State of Connecticut, have invented a new and Improved Viaticum Cabinet-Altar, of which the following is a full, clear, and exact description.

This invention relates to a portable viaticum cabinet altar designed for the administration of the last rites of the church—holy communion and extreme 10 unction. It may also be used for the administration of private baptism and as a private portable 15 altar for general devotion.

An object of this invention is to provide a viaticum altar, which, when opened, will be almost entirely ready for use in emergency at the hour of approaching death, 20 with all the various articles suitable for the priest's use in administering the last rites of the church, in their proper place, whereby confusion incident to the assembling of the various articles required, is avoided.

25 A further object of this invention is to provide a cabinet altar, in which, when opened, everything can be quickly and readily removed, and in which, when closed, everything is held intact, no matter in what 30 position the cabinet may be placed, whether in the process of shipping or otherwise.

These and further objects, together with the construction and combination of parts, will be more fully described hereinafter and particularly set forth in the claims.

Reference is to be had to the accompanying drawings forming a part of this specification, in which similar characters of reference indicate corresponding parts in all 40 the views, and in which—

Figure 1 is a perspective view showing my device open ready for use with one of the plates tilted up out of position, concealing one of the retaining hooks from view and 45 showing its form to better advantage; Fig. 2 is a transverse section, with parts broken away to show the underlying structure; Fig. 3 is a transverse section, with parts broken away to show the underlying structure; Fig. 50 4 is a fragmentary view in elevation, showing one means for holding the removable crucifix in position; Fig. 5 is a fragmentary vertical transverse section through the holy-water font, showing its detachable connection to the body of the box; Fig. 6 is a fragmentary horizontal section showing an-

other view of the detachable connection of the holy-water font; Fig. 7 is a view in elevation, partly in section, showing a modified form of fastening for holding the detachable crucifix in position; Fig. 8 is a fragmentary perspective view showing a detail of the form shown in Fig. 7; Fig. 9 is a detail view of the side stay which holds the cover in an erect position, preventing it from falling either backward or forward, so that the crucifix will be held perfectly vertical when the cabinet is open; and Fig. 10 is a fragmentary sectional view showing the means for connecting the candle-holders to 70 the cabinet.

Referring more particularly to the separate parts of this invention as embodied in the form shown in the drawings, 1 indicates the cabinet container, which may be of any 75 suitable form, and is shown in the form of a box having a body portion 2 and a cover 3 hinged to the body portion in any suitable manner. The front of the box, indicated at 4, is hinged so as to fall downwardly and 80 outwardly, leaving the contents exposed to view, and permitting better access to the interior of the box. The walls of the box and cover may be lined with a suitable covering, preferably of purple, the color of the 85 priest's stole when administering the last rites. The floor of the cabinet or box is preferably covered with a cloth, indicated at 5, which is also purple. The cover 3 is preferably held in an erect vertical position, so 90 that it will not fall either backward or forward when opened, without positive manipulation, by a fastening device 6, comprising in this instance a strip of metal having a slot therein, which engages a pin 7, as more 95 clearly illustrated in Fig. 9. A notch is provided in the side of the slot, so as to engage the pin 7 when the cover is open, and prevents movement of the cover in either direction. The reason for maintaining the 100 cover in a perfectly erect position is so that a crucifix 8, which is attached to the inside of the cover, may be held substantially vertical when the device is in use as an altar. The inside of the cover is preferably provided with a background of folded purple cloth 9, which is disposed in back of the crucifix and offsets the same. The crucifix 8 is preferably detachable, so that it can be 105 handed to the sick person after the sacrament of extreme unction has been administered, as is usual in such cases.

Any suitable means for detachably connecting the cross to the cover, can be used, and in this instance two have been shown. In the form shown in Figs. 1 to 4, a plurality of hooks 10 are provided, which engage on opposite sides of the shaft of the cross under the arms thereof. Engaging the top of the cross, so as to hold it in positive engagement with the hooks 10, there is provided a spring latch 11, which is hinged to the cover, as at 12, and normally exerts a downward pressure on the crucifix when in engagement with the top of the cross thereof. In the form shown in Figs. 7 and 8, a pin 13 is provided in the bottom side of the cover, when in its erect position, which engages a reinforced socket 14 in the bottom end of the shaft of the crucifix. There is also provided a similar socket in the upper end of the shaft of the crucifix, which is engaged by a similar pin 15 connected in a loop 16 of a bow-spring 17, the latter being adapted to yield so as to permit the ready removal or erection of the crucifix.

Disposed symmetrically on opposite sides of the crucifix and secured to the inside of the cover 3 in any suitable manner, there are provided pockets 18 and 19, which form suitable receptacles for napkins 20, one of which may be used to cover the breast of the communicant, and the other may be used by the priest. These pockets may, if desired, however, also be used to hold the rosary and a prayer-book.

Disposed symmetrically in the front of the body of the cabinet, on opposite sides thereof, there are provided candle-holders 21, which are adapted to support in erect position blessed candles 22, and which may be detachably connected to the body in any suitable manner, as for example that indicated in Fig. 10. Here it will be seen that the holder consists of a body portion having a screw cast thereon, which is adapted to be screwed into the material of the body portion, and a saucer or disk 23, which has an opening through which the screw may extend, and which is disposed between the body portion of the candle holder and the body portion of the cabinet, so as to give the required finish. The candles 22, when in their position in the holders 21, would project too high to permit the closure of the cabinet. There is therefore provided a compartment 24, in which the candles may be placed, either before or after they have been placed in the holder 21, and are held in position by an inverted box 25, having a false bottom, as more clearly shown in Fig. 3. The box 25 for facility in use omits cover, and the false bottom, being removable, allows room for extra candles. The box 25 can be readily removed from the compartment 24 by means of a handle 26, which may be of any suitable form, but is shown as being constructed

of a loop of flexible tape. Disposed preferably in the opposite rear corner of the body portion of the cabinet, there is provided a compartment 27, which is symmetrically located with respect to the compartment 24 and the center of the cabinet. This compartment 27 is adapted to contain a box or receptacle 28 which, as will be seen by reference to Fig. 2, is adapted to contain cotton 29, which is used after anointing the sick person with oil. This box is preferably formed coverless, so as to avoid confusion in using the cotton therein, inasmuch as it can be readily inverted in the compartment 27. The compartment 27, besides containing the cotton-container, also provides space for a holy-water bottle 30, in which the holy water used in the viaticum, can be kept. The compartments 24 and 27 are spaced apart from each other a sufficient distance to form a niche, in which may be located an ablution cup 31, which may be used by the priest for his fingers before and after touching the host, and may be used for the water which it is customary to give to the sick person after receiving holy communion. The ablution cup 31 may be held in its position in the niche formed between the compartments 24 and 27, when the cabinet is closed, even when the latter is inverted, by means of a holy-water font 32, which is disposed above the ablution cup. It is to be noted that the position of the font is such that it will be disposed at the foot of the crucifix when the cover is raised. While the font may be supported in any suitable manner, it is preferable that it be detachably connected, and one means of such connection is illustrated in Figs. 5 and 6. Here, there is shown a wedge-key 33, secured in any suitable manner to the back of the body portion of the cabinet and adapted to engage in a corresponding groove or slot 34 in the back of the holy-water font. For the purpose of sprinkling the holy water around the sick person, there is provided a brush 35, which may be secured in any suitable manner to the box 25, as by means of rubber bands 36.

Disposed on the bottom of the body portion of the cabinet, there are provided a plurality of plates 37 and 38, preferably two in number, symmetrically disposed with respect to the center line of the cabinet. One of these plates may be used to hold the ablution cup 31 when in use, and the other may be used to hold the absorbent cotton, salt and bread-crumbs used by the priest after anointing the sick. These plates are preferably connected to the cabinet in such a manner that they can be readily detached and yet so that when in position they will be held firmly, so that they cannot be dislodged, and so that they cannot rattle. Any suitable method of securing the plates may

be used. In this case, I have shown a hook 39 for each of the plates, under which the rims of the plates may be inserted. The front walls of the compartments 24 and 27 5 are rabbeted or provided with a groove, in which the rims of the plates may extend, so as to engage the overhang thus formed in the front walls of the compartments, preventing the plates from slipping out, even 10 when the cabinet is inverted. When the cabinet is closed, the plates are further secured by an overhang on the front 4 on the body portion of the cabinet, which is formed by a groove 40 in the rear side of the front wall. 15 These plates may be provided with any suitable inscription, such as the initials "I. H. S.", showing that they are designed for sacramental purposes. Interposed between the plates 37 and 38, there may be 20 provided a spoon 41, which may be provided with a suitable design, such as a cross, to show that it is used for sacramental purposes, and which may be detachably secured in the cabinet in any suitable manner, as by 25 means of a hook 42.

When the cabinet is closed, it is adapted to be held in its closed position by means of a pivot latch 43, secured to the cover and engaging a hook 44 secured to the movable 30 front of the body portion of the cabinet.

In the use of the device, the cabinet is carried to the bedside of the sick person and preferably, if time and opportunity affords, is located on a small table over which a 35 white linen cloth has been spread, and after opening the cabinet, everything is in position ready for administering the last rites of the church, namely the sacraments of holy communion and extreme unction, with 40 the exception of the host and the oil, which the priest provides, and the candles, which are in the compartment 24. The candles can be readily placed in the holders 21, so that the device will form a complete altar, re- 45 sembling in every respect a stationary altar ready for use and having all the articles necessary for administering the rites to the sick person, by the priest. The box 28 can be readily inverted, so that the cotton therein 50 will be readily accessible for the use of the priest after anointing the sick person. After the altar has been used in the administration of the sacraments designed for, or 55 for general devotions, the device can be readily closed up in a compact form, and

taken away, without any unnecessary confusion or rattling. Even if the cabinet should be inverted, the parts, by reason of their relative position and means of attachment, will be prevented from falling out of 60 position.

The device, by its compactness, size and convenience, is especially suited as an altar for persons who may be traveling or who may have no fixed place of abode, or who 65 may be for the time-being living in the home of another, as it furnishes the means of a convenient and strictly private altar for the purposes of the viaticum, and for private baptism, as also for daily 70 devotions.

While I have shown two embodiments of my invention, I do not wish to be limited to the specific details thereof, but desire to be protected in various changes, alterations and modifications which may come within 75 the scope of the appended claims.

Having thus described my invention, I claim as new and desire to secure by Letters Patent:—

1. The combination with a cabinet, comprising a body portion and a cover hinged to said body portion, of a crucifix secured to said cover in such a position as to assume an erect posture when said cover is opened to its substantially vertical position, a holy- 80 water font secured to said body portion and disposed at the foot of said crucifix when said crucifix is in its erect position, and a plurality of articles in said body portion adapted to be used in the administration of 85 the last rites of the church, said body portion having a movable front, so as to afford an open-altar effect.

2. The combination with a cabinet, comprising a body portion and a cover for said 90 body portion, of a movable front for said body portion with a groove therein forming an overhanging portion, plates over which the said overhanging portion is adapted to extend, and means for engaging and retaining 95 the plates, opposite the movable front of the cabinet.

In testimony whereof I have signed my name to this specification in the presence of two subscribing witnesses.

CHARLES GAY.
